UNITED STATES PATENT OFFICE.

ORRY S. BURTON, OF PENSACOLA, FLORIDA.

REFRIGERATOR.

Application filed July 25, 1924. Serial No. 728,203.

To all whom it may concern:

Be it known that I, ORRY S. BURTON, a citizen of the United States, residing at Pensacola, in the county of Escambia and State of Florida, have invented certain new and useful Improvements in a Refrigerator, of which the following is a specification.

This invention relates to new and useful improvements in refrigerators and has for its principal object to provide a simple and efficient device which may be easily and efficiently carried on an automobile and is principally adapted to be used by persons while touring or camping.

One of the important objects of the present invention is to provide a refrigerator of the above mentioned character, which is of such a construction as to enable the receptacle receiving the various foods to be kept in a cool condition, means being further provided for preventing warm air coming in contact with the receptacle.

A further object of the invention is to provide a refrigerator of the above mentioned character, wherein the parts are so arranged as to enable a person to have ready access thereto whenever necessary.

A further object is to provide a refrigerator of the above mentioned character, which is simple in construction, inexpensive, strong and durable and furthermore adapted for the purposes for which it is designated.

Other objects and advantages of this invention will become apparent during the course of the following description.

In the accompanying drawing forming a part of this specification and in which like numerals designate like parts throughout the same:

Figure 1 is a longitudinal sectional view of my improved refrigerator, and

Figure 2 is a vertical transverse section thereof.

In the drawing wherein for the purpose of illustration is shown the preferred embodiment of my invention, the numeral 1 designates generally the casing of my improved refrigerator and the same is open at its top and is substantially rectangular in design. The casing may be formed of any suitable metallic material and I do not wish to limit myself to the particular kind of material to be used. The casing furthermore includes the spaced inner and outer walls as well as the spaced bottoms whereby a dead air space 2 is provided between the walls and

bottoms in the manner more clearly illustrated in Figure 1 of the drawing. It will of course be understood that the inner and outer walls of the casing are sealed at their upper edges as illustrated at 3.

The casing 1 is provided with a hinged cover 4 and the same also includes the spaced inner and outer walls whereby an air space 5 is provided. The lower edges of the inner and outer walls comprising the cover 4 are sealed as illustrated at 6 in order that the air space 5 may be provided. Any suitable packing such as is shown at 7 is interposed between the sealed upper edges of the casing 1 and the adjacent edges of the cover 4. Any suitable closure means such as is illustrated at A is provided for securing the cover in a locked position with respect to the casing 1.

Adapted to be supported within the casing 1 and resting on the false bottom 9 of the casing is the receptacle 10 which is open at its top, the same being also of substantially the same material as used in the construction of the casing and further being substantially rectangular in design. The receptacle 10 has its walls spaced from the inner walls of the casing whereby an ice compartment or chamber 11 is provided. The ends of the receptacle 10 have supported on their inner faces the strips or guides 12 which provide a means for supporting a shelf or shelves in the receptacle. A hinged cover 13 is provided for the open top of the receptacle 10 and the hinged cover 13 is further provided with a plurality of openings 14, the purpose of which will hereinafter be more fully described. A drain pipe such as is shown at 15 extends through the inner and outer walls of the casing 1 and communicates with the ice compartment or chamber 11 for the purposes well known in the art.

Extending longitudinally within the cover 4 for the casing 1 and communicating at its respective ends with the end walls of the cover is the ventilator tube 16. The end walls of the inner walls of the cover 4 have openings 17 arranged therein for communication with the ends of the tube 16 and the tube is furthermore provided with a plurality of spaced openings 18 the purpose of which will also hereinafter be more fully described. The outer walls of the cover 4 are provided with openings 19 in the front and rear sides thereof

in the manner clearly illustrated in Figure 2 of the drawing. The purpose of the tube 16 and the various openings above set forth is to provide a means whereby the warm 5 air within the casing and the receptacle may be emitted through the openings in the tube and the openings in the cover 4 whereby the warm and foul air will be discharged from the interior of the casing as well as from 10 the receptacle 10, the openings 14 in the cover 13 for the receptacle enabling the warm air to be emitted therefrom.

If desired, the container 10 may have its inner walls lined with porcelain, enamel or 15 any other suitable material. The provision of a refrigerator of the above mentioned character, enables the same to be easily and readily carried on an automobile for use by campers or persons making a long trip and 20 when the ice compartment 11 is filled with ice, the contents within the receptacle will be kept in a cold condition and warm air will be prevented from coming in contact therewith.

25 While I have shown the preferred embodiment of my invention, it is to be understood that various changes in the size, shape and arrangement of parts may be resorted to without departing from the 30 spirit of the invention and the scope of the appended claims.

Having thus described the invention, what I claim is:—

1. A refrigerator comprising a substantially rectangular shaped casing open at 35 its top, said casing including spaced inner and outer side walls and bottom, forming a dead air space therebetween, a hinged cover for the casing, a receptacle within the casing 40 supported on the false bottom and spaced from the inner walls of the casing, forming an ice compartment around the receptacle, means for conducting the warm air from the interior of the casing and the receptacle 45 outwardly through the cover of the cas-

ing, said means comprising an elongated tube supported in the cover of the casing, said cover having openings therein communicating with the ends of the tube, said tube having openings therein communicat- 50 ing with the interior of the casing.

2. A refrigerator comprising a substantially rectangular shaped casing open at its top, said casing including spaced outer and inner side walls and bottom, the upper edges 55 of the walls being sealed to provide a dead air space between the walls, a hinged cover for the casing including spaced inner and outer walls, a receptacle within the casing and spaced from the inner walls thereof 60 forming an ice compartment around the receptacle, said receptacle having its top open and provided with a hinged cover, said cover for the receptacle having openings therein, a tube on the inner side of said cover having the ends thereof communicating with openings provided in the inner end walls of the cover, said tube having openings arranged therein and communicating with the interior of the casing and the receptacle therein, the outer side walls of the cover for the casing having openings therein where- 70 by warm air within the receptacle and casing may be discharged outwardly through the tubes and the cover for the cas- 75 ing.

3. A refrigerator comprising a casing of substantially rectangular design and being open at its top, a cover therefor, and means for conducting the warm air from the interior of the casing outwardly through the cover, said means comprising an elongated tube supported in the cover of the casing, the cover being provided with openings for communication with the respective ends of the tube, said tube having openings therein communicating with the interior of the casing. 85

In testimony whereof I affix my signature.
ORRY S. BURTON.
